UNITED STATES PATENT OFFICE.

NEWTON D. MERWIN, OF HIGGANUM, CONNECTICUT, ASSIGNOR OF ONE-HALF TO
PHILIP W. PORTER, OF HIGGANUM, CONNECTICUT.

PLANE IRON.

1,419,400.

Specification of Letters Patent. Patented June 13, 1922.

Application filed May 20, 1921. Serial No. 471,152.

To all whom it may concern:

Be it known that I, NEWTON D. MERWIN, a citizen of the United States, and a resident of Higganum, in the county of Middlesex and State of Connecticut, have invented certain new and useful Improvements in Plane Irons, which improvements are fully set forth in the following specification.

- 0 This invention relates to improvements in devices of that class available in conjunction with a suitable stock for surface-dressing purposes, such devices being commonly known as plane irons.
5 The object of this invention is to provide a plane iron which shall embody a displaceable cutting-edge; be simple and inexpensive as regards its construction, durable efficient and reliable in practical service, and
0 which shall possess certain well-defined advantages over prior analogous constructions.

The invention consists in the combinations, details and parts to be hereinafter more particularly referred to, and whereby
5 the attainment of the foregoing object is rendered practicable.

The invention is clearly illustrated in the accompanying drawing, wherein:

Fig. 1 is a view showing in plan and detached a capped plane iron embodying my said improvements, a portion of the cap-plate and displaceable cutting-blade made use of being broken away.

Fig. 2 is a central, longitudinal section of same, as along the dotted line 2—2 of Fig. 1.

Fig. 3 is a bottom plan view of the device, the cutting-blade thereof being partially displaced.

Fig. 4 is a detail view showing partially in elevation and partially in section my improved plane iron in its application to a stock.

Having reference to the accompanying drawing, wherein similar reference-characters denote like parts throughout the respective views, I, in carrying out my present invention, provide a plane iron 2 of the customary general form, and displaceably mount thereon, at its advance end, a cutting-blade 2'.

While the mounting of the cutting-blade 2' on the iron 2 may be effected in any convenient and appropriate manner, I purpose in this connection and by preference, to fit the iron 2, somewhat rearwardly of its ad-

vance end, with a transverse dovetailed depression 3, for the reception endwise and by a sliding action only of the transverse dovetailed rib 4 with which the cutting-blade 2' is provided at the rear face thereof and somewhat rearwardly of its cutting-edge, the opposite sidewalls of the depression 3 being duly undercut to this end.

While casual displacement of the cutting-blade aforesigned from its position of service relatively to the iron 2 is obviated in practice by the opposite side-walls of the stock, as 5, in conjunction with which the assembled iron and cutting-blade may be used, it is advisable that said cutting-blade be directly subjected to a clamping stress, whereby the same shall become locked with substantial rigidity in its disposition relatively to said iron; and to this end I provide the usual cap-plate 6, which is superimposed, as in common practice, upon the iron 2 and is there firmly held by means of a suitable lock-screw 7.

The lock-screw 7, fitted with a head 7', projects through, as in common practice, both the cap-plate 6 and the iron 2 and has a threaded engagement with the latter. Hence, turning said lock-screw duly homeward causes its head 7' to engage the cap-plate 6 thereunder and thereby causes the advance edge of the cap-plate to bear with a clamping effect upon the cutting-blade thereunder, whereby the latter becomes locked in its disposition relatively to the advance end-portion of the iron 2 thereunder.

In practice the advance end of the cap-plate 6 is best curved downwardly somewhat, substantially as indicated in the drawing.

As to the utility of my improved plane iron, it may be pointed out that since no cutting-edge is required for the iron proper, the same may be formed from material less expensive than is required where the cutting-edge is formed directly thereon and the iron is subjected to a hardening process, as in common practice.

Again, should the cutting-blade of my improved plane iron become niced or otherwise materially injured in service, the same may, when rendered by such injury unsuitable for re-grinding, be discarded and a fresh one substituted therefor, the cost of each of such cutting-blades being quite nominal and the user keeping himself supplied,

as occasion may dictate, with an emergency supply thereof.

It will be quite apparent that each cutting-blade made use of is best formed from steel 5 and hardened.

My improved plane iron, together with the cap-plate locked in position thereon as stated, is inserted into and adjusted within the stock 5 and there removably held by means of a 10 suitable key or wedge 8, all as in common practice.

It will be seen that my improved plane iron is well adapted for the purposes for which it is intended, and further that the 15 same may be modified to a considerable extent, particularly as regards the means availed of for displaceably mounting the cutting-blade on the plane iron proper, without material departure being made from the 20 spirit and principle of my invention as set forth in and coming within the scope of the claims hereto appended and forming a part hereof.

I claim:

25 1. An iron of the class herein described formed with a dovetailed depression extending continuously transversely along one face thereof somewhat rearwardly of its advance end, said iron fitted with a cutting-blade 30 having a dovetailed rib extending transversely along one face thereof somewhat rearwardly of its cutting-edge, said rib having an endwise sliding fit only within the depression aforenamed.

2. An iron of the class herein described 35 formed with a dovetailed depression extending continuously transversely along one face thereof somewhat rearwardly of its advance end, said iron fitted with a cutting-blade having a dovetailed rib extending transversely along one face thereof somewhat rearwardly of its cutting-edge; and locking means for preventing casual displacement of said cutting-blade from its position of service relatively to said iron, said rib having 40 an endwise sliding fit only within the depression aforenamed.

3. An iron of the class herein described 45 formed with a dovetailed depression extending continuously transversely along one face thereof somewhat rearwardly of its advance end, said iron fitted with a cutting-blade having a dovetailed rib extending transversely along one face thereof somewhat rearwardly of its cutting-edge; a cap-plate 5 superimposed on said iron and bearing at its advance end on the cutting-blade thereunder; and a lock-screw, said lock-screw projecting through both the cap-plate and said iron and having a threaded engagement 6 with the latter, and adapted, when turned duly homeward, to draw and hold the cap-plate into clamping engagement with the cutting-blade thereunder, said rib having an endwise sliding fit only within the depression aforenamed.

NEWTON D. MERWIN.
